[57] CLAIM

The ornamental design for playground equipment step, as shown and described.

DESCRIPTION

FIG. 1 is a perspective view of a playground equipment step showing our new design.

FIG. 2 is a side view of the step shown in FIG. 1, the two side views being identical.

FIG. 3 is a top view of the step shown in FIG. 1, as seen along line-of-sight III in FIG. 2.

FIG. 4 is a bottom view of the step shown in FIG. 1, as seen along line-of-sight IV in FIG. 3.

FIG. 5 is a front view of the step shown in FIG. 1, as seen along line-of-sight V in FIG. 2.

FIG. 6 is a back view of the step shown in FIG. 1, as seen along line-of-sight VI in FIG. 2.
